[57] **CLAIM**

The ornamental design for a specialty garden tool for
delicately planted systems, as shown and described.

DESCRIPTION

FIG. 1 is a perspective view of a specialty garden tool
for delicately planted systems showing my new design
therefor;

FIG. 2 is a left side elevational view;

FIG. 3 is a top plan view;

FIG. 4 is a bottom plan view;

FIG. 5 is a right side elevational view;

FIG. 6 is a rear elevational view;

FIG. 7 is a front elevational view; and,

FIG. 8 is a perspective view of a specialty garden tool
for delicately planted systems; the broken line drawing
representing a partial human form is for purposes of
scale and illustration only and forms no part of my
design.
